(74) Attorney, Agent, or Firm — Woods Oviatt Gilman,
 LLP; Ronald J. Kisicki, Esq.

(57) **CLAIM**

The ornamental design for the actuator module for an electric strike assembly, as shown and described.

DESCRIPTION

FIG. 1 is a front right perspective view of an actuator module for an electric strike assembly of our new design; FIG. 2 is a front view thereof;

FIG. 3 is a top view thereof;

FIG. 4 is a back view thereof;

FIG. 5 is a bottom view thereof; and,

FIG. 6 is a left side view thereof with the right side view being a mirror image thereof.

The portions of the drawings shown in broken lines form no part of the claimed design.
